DANIEL J. GALE, OF SHEBOYGAN FALLS, WISCONSIN, ASSIGNOR OF ONE-HALF HIS RIGHT TO AARON HUYCK, OF SAME PLACE.

Design No. 4,649, dated February 14, 1871.

DESIGN FOR A CALENDAR CLOCK-DIAL.

The Schedule referred to in these Letters Patent and making part of the same.

To all whom it may concern:

Be it known that I, DANIEL J. GALE, of Sheboygan Falls, in the county of Sheboygan and in the State of Wisconsin, have invented a new and useful Design for an Astronomical and Calendar Clock-Dial; and do hereby declare that the following is a full, clear, and exact description thereof, reference being had to the accompanying drawing making a part of this specification.

This design consists of a large dial, having within or upon its face two small dials arranged above and below its center, and upon opposite sides horizontally of said center two smaller dials, all of which, as well as said large dial, are intended for use with suitable pointers or hands.

The edge of the large dial is divided into thirty-one equal spaces, which are consecutively numbered from one upward, and serve, by the aid of a suitable hand, to indicate the days of the month.

The dial above the center of the large dial is divided and marked in the usual manner, so as to indicate the hours of the day, while the corresponding dial below said center is provided with three series of divisions, the outer of which contains fifty-two equal spaces, each of which contains, upon the outside of the circle, figures denoting the average time per week, for one week of the year, at which the sun sets, while upon the inside of said circle is shown the average time of sunrise during the same week.

The second circle is also divided into fifty-two equal spaces, which are consecutively numbered from one upward, and indicate the number of seventh days or weeks from the first day of the year to its close, while upon the inner side of said circle are the days of the month upon which each seventh day falls.

The inner circle is divided into twelve equal spaces, which contain the names of the months, and are so

arranged with reference to the other circles or series of figures as that one pointer or hand shall correctly indicate upon each the especial information contained therein for each successive week of the year.

The small dial upon the right of the large dial is divided around its exterior into twenty-nine equal spaces, which are successively numbered from one upward, and denote the moon's age in days; while at four equidistant points within the line of figures are placed the characters commonly used to denote the stages or "quarters" of the moon, said characters being so arranged with reference to said figures as to bring the full moon at the middle of the lunar month, or at the fourteenth and one-half day.

The small dial at or upon the left side of the large dial is divided into seven equal spaces, each of which contains one of the names of the days of the week, said names being arranged in regular succession around the interior of the line of divisions.

The dial is now complete, and contains all needed information with relation to the daily, weekly, and monthly changes during a year, which information, by the arrangement of the smaller dials, can be easily and quickly obtained for any specified day in said year.

Having thus fully set forth the nature and merits of my invention,

What I claim as new is—

The hereinbefore-described design for an astronomical calendar clock-dial, substantially as and for the purpose set forth.

In testimony that I claim the foregoing I have hereunto set my hand this 9th day of January, 1871.

DANIEL J. GALE.
